CLAIM

The ornamental design for a dental cartridge, as shown and described.

DESCRIPTION

FIG. 1 is a top perspective view of a dental cartridge showing my new design;

FIG. 2 is a top plan view thereof, the bottom plan view being identical;

FIG. 3 is a front elevational view thereof, the rear elevational view being identical;

FIG. 4 is a top perspective view of a second embodiment of the dental cartridge;

FIG. 5 is a top plan view of FIG. 4, the bottom plan view being identical;

FIG. 6 is a front elevational view of FIG. 4, the rear elevational view being identical;

FIG. 7 is a top perspective view of a third embodiment of the dental cartridge;

FIG. 8 is a top plan view of FIG. 7, the bottom plan view being identical;

FIG. 9 is a front elevational view of FIG. 7, the rear elevational view being identical;

FIG. 10 is a top perspective view of fourth embodiment of the dental cartridge including a closed flange at one end thereof, the bottom view being identical thereto, and the rear end view of the cartridge is the same as the FIG. 3;

FIG. 11 is a top perspective view of fifth embodiment of the dental cartridge, the bottom view being identical thereto, and the end view of the cartridge is the same as the FIG. 3;

FIG. 12 is a top perspective view of a sixth embodiment of the dental cartridge, the bottom view being identical thereto, and the rear end view of the cartridge is the same as the FIG. 6;

FIG. 13 is a top perspective view of a seventh embodiment of the dental cartridge, the bottom view being identical thereto, and the rear end view of the cartridge is the same as the FIG. 6;

FIG. 14 is a front and top perspective view of a eighth embodiment of the dental cartridge, the rear and bottom view being identical thereto;

FIG. 15 is a front and top perspective view of a ninth embodiment of the dental cartridge, the rear and bottom view being identical thereto; and,

FIG. 16 is a front and top perspective view of a tenth embodiment of the dental cartridge, the rear and bottom view being identical thereto.
